DESIGN FOR A SAUCER OR SIMILAR
ARTICLE

Alfred Langford, Hanford, Stoke-on-Trent, England, assignor to The Coalport China Company (John Rose & Co.) Limited, Stoke-on-Trent, England

Application June 5, 1939, Serial No. 85,348. In Great Britain March 21, 1939. Term of patent 14 years

To all whom it may concern:

Be it known that I, Alfred Langford, a British subject, residing at "Stokesay", Wilton Road, Hanford, Stoke-on-Trent, England, have invented a new, original, and ornamental Design for a Saucer or Similar Article, of which the following is a specification, reference being had to the accompanying drawing, forming part thereof.

In the drawing the figure is a top plan view of a saucer showing one repeat of my design, the broken lined segment indicating that the design therein is to be repeated around the rim of the saucer.

I claim:

The ornamental design for a saucer or similar article, as shown and described.

ALFRED LANGFORD.
